UNITED STATES PATENT OFFICE

ADOLF VAN CANEGHEM, OF WATERLOO, IOWA

SELF-CLEANING LOADING DEVICE

Application filed March 19, 1928. Serial No. 262,800.

My invention relates to self-cleaning loading devices, and the object of my improvements is to supply for loading manure or other material from a pile into a conveyance or other receptacle, manually controllable means for effecting that purpose, including coacting grab forks and devices positioned in such an operative relation thereto as will permit the devices to function on the spreading apart of the forks in discharging a load by also detaching and discharging adherent material on the forks.

This object I have accomplished by the means which are hereinafter described and claimed, and which are illustrated in the accompanying drawings, in which Fig. 1 is a front elevation of my self-cleaning loading device with its forks in closed relation, and Fig. 2 is a side elevation of the same.

My invention is not restricted to the precise construction and arrangement of parts herein shown and described, or to the various details thereof, as the same may be modified or rearranged in various particulars without departing from the spirit and scope of my invention, one practical embodiment of which has been herein illustrated and described without attempting to show all of the various forms and modifications in which my invention might be embodied.

My device is particularly adapted for use in the loading of a wagon or a manure spreader from a pile of manure on the ground or in a stable, but I have not shown such a conveyance or receptacle or the devices such as may without novelty be employed to hoist the loader after filling it, moving it then over the wagon or receptacle for discharge thereinto, and then returning it to its initial position for a refilling.

In the drawings, therefore, the numeral 1 denotes a horizontal cross-bar upon which is fixed a longitudinally disposed bar having its middle part bent at each side of the center of the device in an elongated loop 2, an eye-

bolt 3 then having its stem fastened in the middle of the loop to project upwardly and receive a cable for lifting it after loading for transportation to and over a wagon.

The cross-bar 1 has at each end downwardly convergent depending and longitudinally open roll-ways 5-6 connected by an integral cross member 7, and the numeral 9 denotes headed rollers which are seated to roll in said roll-ways.

Below said cross-bar 1 and the roll-ways 5-6 pivotally connected grab forks 14 and 15 are suspended on said rollers 9. The stems 11 and 12 of the forks 15 and 14 respectively are medially crossed and pivotally connected together on a pintle 13 in the vertical medial line of the device. The upper ends of the stems are constructed with furcations 10 and said rollers 9 are mounted between said furcations on connecting pintles. Below the pintle 13 the stems 11 and 12 are preferably of squared cross section, but the furcations 14 and 15 from the cross-bar portions 33 on said stems 11 and 12 are preferably of circular cross section to terminate in sharp pronged points, the furcations being recurved to have their pronged terminations slightly overlap when closed together.

To the outer furcations 14 and 15 are secured the apertured ears 32 at about their locations of recurving. Relatively long coiled tension springs 8 are at the top connected to the opposite terminations of T-heads 4 on the top cross bar 2 or integral therewith, and the lower ends of said springs are secured in the apertured ears 32.

The ears 32 may be the outturned terminations of rigid bars 34 secured across the outer edges of the furcations 14 and 15 to reinforce them. A short distance below the medial pintle 13 an inwardly projecting horizontal arm 16 having some upwardly directed terminal teeth 17 is fixed to each outer furcation 14, and on each side of the furcations 15 an arm 18 is medially pivoted on a stud 90

20 thereto, the outer ends of the arms 18 being integrally connected without the furcations 15 by a cross part 21 to whose middle a depending pull-cord 22 is secured. The inner termination of each arm 18 has depending teeth 19 to engage the teeth 17 on the respective arm 16 thereunder, when the furcations 14 and 15 are closed together in the position illustrated, and held in engagement 5 10 yieldingly by means of a small coiled tension spring 25 connected from each arm 18 to a short fixed arm 24 thereunder on the outer furcation 15. A rigidly mounted stop-arm 23 on each said outer furcation 15 under each 15 arm 18 limits downward swinging of the inner toothed termination of the arm.

Slightly below said arms 16 and 18 are inwardly directed arcuate arms 26 fixed on the outer furcations 14 and 15 formed on the 20 same radius centered at the pintle 13 and having longitudinal slots 27 also of arcuate shape to receive slidingly the pintles 28 which are secured across the tops of downwardly divergent plates 29 which are at the bottom secured 25 rigidly together by means of cross bars 30. Cleaner bars or teeth 31 have their upper spaced parts welded or otherwise fixed on the outer faces of the depending plates 29 to depend therefrom inclinedly in the interspaces 29 of the furcations 14 and 15 and of sufficient length to permit the whole lower effective lengths of said curvate furcations to sweep past them when the furcations are spread apart by the reactions of the springs 8 shown 33 under tension in the figures, and when the toothed arms 16 and 18 are disengaged.

The above described device may be suspended on a cable end-connected to the eye-bolt 3 from a carriage of any desired type 10 mounted for to and fro movements along an elevated track above a wagon-box, manure spreader box or other receptacle, and with the arms 16 and 18 disengaged by use of the pull-cord 22 and the furcations spread apart. An 15 operator at a pile of manure or other material may then manually close together the furcations 14 and 15 in grabbing a portion of the pile thereon, the toothed terminations of the arms 18 riding over and mating with the 20 toothed ends of the arms 16 and held secured by the springs 25. The springs 8 are thus placed under lengthwise tension as shown. The device so loaded may then be hoisted, transported above the receptacle, and an operator upon or near the latter may use the pull-cord 22 to disengage the arms 18 from the fixed arms 16, the springs 8 then strongly reacting to spread apart the furcations 14 and 15, discharging the load. Simultaneously as 25 the furcations 14 and 15 sweep across the interposed relatively fixed teeth 31 the latter disengage and discharge adherent portions of the sticky load on the furcations. The device is then returned and lowered for another 65 filling.

Having described my invention, what I claim as new, and desire to secure by Letters Patent, is:

1. A device of the character described, comprising like depending recurved furcations having crossed and pivoted shanks with terminal rollers mounted thereon, a transverse structure containing depending inwardly inclined rollways on which said rollers are mounted, resilient connections yieldingly connected between said structure and said furcations below their pivotal connections, and releasable locking means on and to secure the furcations together in one relative position. 70 75

2. A device of the character described, comprising like depending recurved furcations having crossed and pivoted shanks with terminal rollers mounted thereon, a transverse structure containing depending inwardly inclined rollways on which said rollers are mounted, detachably engaged locking devices on the opposed furcations adapted to interlock when the furcations are in closed together positions, and resilient connections yieldingly connected between said structure and said opposite furcations below their pivotally connected shanks. 80 85 90

3. A device of the character described, comprising like depending recurved furcations having crossed and pivoted shanks with terminal rollers mounted thereon, a transverse structure containing depending inwardly inclined rollways on which said rollers are mounted, resilient connections yieldingly connected between opposite ends of said structure and the opposite furcations below their pivotal connections, cross members positioned across the interspace of the opposite furcations, scraper arms rigidly mounted on the opposite terminations of said cross members to normally be positioned to project between the said furcations for the latter to sweep thereacross when spread apart, and 100 105 110 115 120 125 130

4. A device of the character described, comprising like depending recurved furcations having crossed and pivoted shanks with terminal rollers mounted thereon, a transverse structure containing depending inwardly inclined rollways on which said rollers are mounted, detachably engaged locking devices on the opposed furcations adapted to interlock when the furcations are closed together, resilient connections yieldingly connected between opposite parts of said structure and the opposed furcations below their pivotal connections, cross members positioned across the interspace of said opposite furcations, plates mounted fixedly and inclinedly upon the opposite ends of said cross members, scraper arms fixed upon said plates dependingly to project through the interspaces of the furcations to permit the latter to sweep there- 120 125 130

across while being spread apart, inwardly projecting arms on said opposite projections having arcuate slots formed on a radius from the pivotal connection of said shanks, and
5 pintles on the upper parts of said plates seated in said slots whereby said cross members are supported upon the opposite furcations medially therebetween with relative sliding connections.

10 In testimony whereof I affix my signature.
ADOLF VAN CANEGHEM.
